UNITED STATES PATENT OFFICE

160,902

BOOKSTAND FOR BIBLE OR SIMILAR ARTICLE

Mary C. Suhren, Teaneck, N. J.

Application December 21, 1949, Serial No. 6,762

Term of patent 14 years

(Cl. D33—2)

To all whom it may concern:

Be it known that I, Mary C. Suhren, a citizen of the United States of America, residing at Teaneck, county of Bergen, and State of New Jersey, have invented a new, original, and ornamental Design for a Bookstand for Bible or Similar Article, of which the following is a specification, reference being had to the accompanying drawing, forming a part thereof wherein:

Figure 1 is a perspective view of a bookstand for Bible or similar article, showing my new design, and

Figure 2 is a view in end elevation of the bookstand for Bible or similar article.

I claim:

The ornamental design for a bookstand for Bible or similar article, as shown.

MARY C. SUHREN.
